AUTOMATIC SEAR

Earle M. Harvey, Agawam, Mass., assignor to the
United States of America as represented by the
Secretary of War

Original application February 11, 1949, Serial No.
75,921. Divided and this application April 4,
1950, Serial No. 153,952

2 Claims. (Cl. 89—149)

(Granted under Title 35, U. S. Code (1952),
sec. 266)

1

The invention described herein may be manufactured and used by or for the Government for governmental purposes without the payment of any royalty thereon.

This invention relates to those firearms arranged to be selectively operated in either semi-automatic or full automatic fire and relates more particularly to an automatic sear for the firing mechanism thereof.

This application is a division of my copending application Serial No. 75,921 filed February 11, 1949.

The object of this invention is to provide in an automatic and semi-automatic firearm an improved automatic sear arranged to block the fall of a hammer until such time as the firearm bolt reaches a fully locked battery position.

The specific nature of the invention as well as other objects and advantages thereof will clearly appear from a description of a preferred embodiment as shown in the accompanying drawings in which:

Fig. 1 is a right side fragmentary view of the firearm showing the bolt in the locked battery position and the automatic sear in its hammer releasing position;

Fig. 2 is a longitudinal sectional view of the firearm showing the bolt in a recoiled position and the automatic sear in position to block the fall of the hammer;

Fig. 3 is a fragmentary detail view of the firing mechanism set for automatic fire and showing how the fall of the hammer is blocked by the automatic sear;

Fig. 4 is a perspective view of the automatic sear; and

Fig. 5 is a cross-sectional view taken along the line 5—5 in Fig. 1.

The firearm illustrated in Fig. 1 generally comprises a receiver 5, a barrel 6 threadably secured to the forward end thereof, a reciprocating bolt 7 having a locking block 8 associated therewith in a manner more fully described in my aforementioned copending application, and a trigger housing 9 suitably secured to the underside of receiver 5.

Bolt 7 is arranged to be fully locked in battery position when locking block 8 has been pivoted upwardly to the position indicated by the dotted outline thereof shown in Fig. 1. An operating slide 26 is operatively associated with locking block 8 by means of a camming lug 25. When locking block 8 is in its bolt locking position, slide 26 is in a full battery position.

A trigger 28 is pivotally secured in housing 9

5 by means of a transverse pin 29. A primary sear 45 is pivotally associated with trigger 28 and is arranged to retain a hammer 35 in its cocked position during semi-automatic fire when trigger 28 is held in its pulled firing position. Upon release of trigger 28, a hammer spring 31 rotates such trigger in a counterclockwise direction whereupon cocking engagement of hammer 35 is transferred from sear 45 to a lug 33 on trigger 28. Thus trigger 28 must be again pulled to initiate another cycle of semi-automatic fire.

10 However, as more fully described in copending application Serial No. 164,578 filed May 26, 1950, a selector mechanism 53 having a depending sear engaging portion 65 is provided to pivot sear 45 rearwardly with respect to trigger 28 so that when hammer 35 is cocked by the recoiling movement of bolt 7 and locking block 8, no engagement of such hammer with sear 45 will take place. Thus when trigger 28 is pulled, automatic fire will ensue as long as cartridges 84 are present within a magazine 88.

15 An automatic sear designated generally by the numeral 43 is provided to hold hammer 35 in substantially the cocked position in the absence of engagement thereof by either primary sear 45 or trigger 28. Sear 43 comprises a forwardly extending arm 101 which terminates in an upwardly projecting portion 102 and a rearwardly extending arm 103. Arms 101 and 103 are spaced apart as best shown in Fig. 4 by a cylindrical cross bar 104 having parallel slotted surfaces on the top and bottom thereof as best shown at 105. Receiver 5 is provided with a transverse hole 106 for rotatably mounting sear 43 thereto. A vertical passage 107 extends downwardly from hole 106 and serves to provide access for cross bar 104 during assembly to and disassembly from receiver 5. When so assembled, arm 103 lies adjacent the inner wall surface of receiver 5 while arm 101 lies along the outside surface thereof with the upwardly projecting portion 102 arranged to engage in a longitudinal cam track 108 formed along the underside of operating slide 26. Cam track 108 extends from a point slightly forward of the extreme rear end of slide 26 and terminates adjacent a handle 109 projecting laterally therefrom. A camming shoulder 110 is provided at the rear end of track 108 for a purpose to be described.

20 A substantially U-shaped magazine guard 111 is fixedly secured to the forward end of trigger housing 9 and serves to enclose magazine 88. A lug 112 projects laterally and outwardly from guard 111 and is provided with a vertical counter-

bored hole 113. A bracket 114 is suitably secured to the forward end of trigger housing 9 and above magazine guard 111 and is provided with an outwardly projecting arm 115 so disposed that a counterbored hole 116 therein is spaced apart from counterbored hole 113 but in axial vertical alignment therewith. A plunger 117 extends through holes 113 and 116 and a collar portion 118 thereon is arranged to seat against a shoulder 119 formed by the counterbored portion of hole 116. A helical coil spring 120 surrounds plunger 117 and seats between the underside of collar portion 118 and the counterbored portion of hole 113. Thus the top end of plunger 117 is constantly urged upwardly against a flat surface 121 on the underside of forwardly extending sear arm 101 to rotate automatic sear 43 in a counter-clockwise direction so that upwardly projecting portion 102 thereon engages in cam track 103. However when operating slide 26 approaches its last increment of movement into battery position, shoulder 110 in cam track 103 cams sear arm 101 downwardly against the bias of spring 120 thereby raising the other arm 103 out of the path of movement of a lug 42 formed on the right side of hammer 35.

Referring now to Fig. 1 of the drawings, there is shown the firing mechanism of this invention in position for semi-automatic fire. Bolt 7 is in locked battery position and operating slide 26 is also in its battery position. As a result, camming shoulder 110 on slide 26 has rotated automatic sear 43 so that the rear end of arm 103 is raised out of the path of movement of lug 42 on hammer 35 which is retained in a cocked position by trigger 28. Selector mechanism 53 is in its semi-automatic position and therefore out of contact with sear 45 thus allowing hammer spring 51 to pivot sear 45 up against the rear edge of trigger 28.

Assuming a cartridge 84 to be chambered in barrel 6, trigger 28 is pulled thereby releasing hammer 35 from cocking engagement therewith. The energy stored up in hammer spring 51 during cocking rotates hammer 35 to discharge cartridge 84. Operating slide 26 is driven to the rear in the manner conventional to gas operated firearms and serves to unlock bolt 7. During such unlocking movement of slide 26, the underside thereof has moved off the upwardly projecting portion 102 of sear arm 101 and has brought cam track 103 into position to be engaged by portion 102 under the bias of spring pressed plunger 117. This rocking movement of automatic sear 43 brings the rear end of arm 103 into the path of movement of lug 42 on hammer 35. The recoil travel of bolt 7 rotates hammer 35 in a conventional manner to be first engaged by sear 45. Up to this time the action of the moving parts has been so rapid that the operator of the firearm has not had sufficient time to release trigger 28 from its pulled position. Upon doing so, however, sear 45 becomes disengaged from hammer 35 whereupon trigger 28 becomes engaged therewith. Should hammer 35 fail to engage either sear 45 or trigger 28 for any reason, prior to the termination of battery movement of operating slide 26, the rear end of arm 103 effectively blocks the fall of hammer 35 by engaging lug 42 thereon. But when both slide 26 and bolt 7 reach battery position, automatic sear 43 is rendered inoperative in the manner previously described. Pulling of trigger 28 then initiates another cycle of operation.

When it is desired that the firearm operate as

a fully automatic weapon, i. e., continue to fire as long as trigger 28 is held in the pulled position and cartridges 84 are available for chambering in barrel 6, selector mechanism 53 is rotated clockwise of the position indicated in Fig. 1. The depending sear engaging portion 65 of selector mechanism 53 is thereby moved to rock sear 45 rearwardly away from a hammer engaging position. Since trigger 28 remains pulled, automatic sear 43 here provides the means for retaining hammer 35 in its cocked position until bolt 7 is locked in battery position and slide 26 has completed its forward travel. If such automatic sear 43 were not available, hammer 35 would follow the counter-recoiling bolt 7 and consequently would lack sufficient impact force to discharge the chambered round 84.

It will be readily appreciated by those skilled in the art that the automatic sear 43 here described not only provides means during automatic fire for retaining a hammer in its cocked position until the firearm breech is locked but also provides safety means for preventing accidental fall of the hammer prior to locking of the bolt during semi-automatic fire.

I claim:

1. In an automatic and semi-automatic firearm having a receiver, a bolt, a locking block pivotally connected to said bolt, said bolt and said block slidably mounted in the receiver for reciprocable movement between a locked battery position and a recoil position, an operating slide slidably mounted to the receiver for reciprocable movement between a battery and a recoil position, said slide being operatively connected to said locking block, a hammer pivotally mounted in the receiver for movement between a cocked and a fired position and arranged to be pivoted toward the cocked position by said locking block during recoil thereof, an automatic sear rotatably secured to the receiver, said sear having a forwardly projecting arm and a rearwardly projecting arm connected by a cross bar portion whereby said first mentioned arm lies adjacent the outer wall of the receiver and said second mentioned arm lies adjacent the inner wall thereof, said slide having a cam track, an upwardly projecting portion on said forwardly projecting sear arm arranged to engage in said cam track, said hammer having a lug on the right side thereof arranged to be engaged by the rear end of said rearwardly projecting sear arm, and cam means on said slide for rotating said forwardly projecting arm on said automatic sear out of engagement with said cam track at the conclusion of forward movement of said slide into battery position whereby said rearwardly extending sear arm is pivoted out of the path of movement of said hammer lug after said bolt and said locking block are in locked battery position.

2. The structure defined in claim 1 including a spring pressed plunger slidably mounted to the receiver for vertical upward movement against the underside of said forwardly projecting sear arm, and stop means for limiting the upward movement of said plunger.
